(57) **CLAIM**

We claim the ornamental design for a footwear care machine, as shown and described.

DESCRIPTION

FIG. 1 is a front perspective view of a footwear care machine showing a new design;

FIG. 2 is a bottom perspective view thereof;

FIG. 3 is a front view thereof;

FIG. 4 is a rear view thereof;

FIG. 5 is a left-side elevation view thereof;

FIG. 6 is a right-side elevation view thereof;

FIG. 7 is a top plan view thereof;

FIG. 8 is a bottom plan view thereof;

FIG. 9 is an enlarged perspective view of the sterilizing dryer, shown separately from the main body of the footwear care machine, showing in a retracted position;

FIG. 10 is an enlarged perspective view of the sterilizing dryer, shown separately from the main body of the footwear care machine, showing in an extended position;

FIG. 11 is an enlarged perspective view of the sterilizing dryer, shown separately from the main body of the footwear care machine, showing a retracted position in a state of use;

FIG. 12 is an enlarged perspective view of the sterilizing dryer, shown separately from the main body of the footwear care machine, showing an extended position in a state of use; and,

FIG. 13 is a perspective view of the footwear care machine showing the sterilizing dryer in an extended position.
The dot-dot-dash broken lines shown in the figures are for the purpose of illustrating the detail markers for the enlarged
